Primary Examiner — Kendra Leslie Hamilton

(57) **CLAIM**

The ornamental design for a feeding bottle, as shown and described.

DESCRIPTION

FIG. 1 is a front, top perspective view of a feeding bottle, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of the feeding bottle of FIG. 1, shown open in a second configuration for clarity of disclosure; and,

FIG. 10 is an enlarged detail view of detail “10”, identified in FIG. 2.

The evenly spaced broken lines and all areas within depict portions of the feeding bottle that form no part of the claimed design.

1 Claim, 10 Drawing Sheets
